UNITED STATES PATENT OFFICE.

JOHN B. BARTHOLOMEW, OF PEORIA, ILLINOIS, ASSIGNOR TO AVERY MANUFACTURING COMPANY, OF PEORIA, ILLINOIS.

CULTIVATOR.

SPECIFICATION forming part of Letters Patent No. 701,004, dated May 27, 1902.

Application filed June 6, 1896. Serial No. 594,581. (No model.)

To all whom it may concern:

Be it known that I, JOHN B. BARTHOLOMEW, a citizen of the United States, residing at Peoria, in the county of Peoria and State of Illinois, have invented certain new and useful Improvements in Cultivators; and I do declare the following to be a full, clear, and exact description of the invention, such as will enable others skilled in the art to which it applies to make and use the same, reference being had to the accompanying drawings, and to the letters of reference marked thereon, which form a part of this specification.

Figure 1 is a longitudinal section of a cultivator embodying my improvements, the parts being represented in working position by full lines and in their raised or inactive position by dotted lines. Fig. 2 is a cross-section taken on a line $\alpha-\alpha$ of Fig. 1. Fig. 3 is a detached perspective view of the spring lifting devices and portions of adjacent parts, the spring being conventionally indicated. Fig. 4 is a vertical cross-section of the sliding bar M looking toward the lever, to which one end of the spring is connected.

In the drawings, A A indicate the ground-wheels; B, the crank-axle; C, the tongue; D D, the longitudinal frame-bars, and D' the seat. These may be of any well-known or of any preferred form.

E E indicate the beams or drag-bars, to which are attached the standards or shanks for the shovels. They are pivotally connected with the frame, preferably by means of clips G, secured to the downward and inward turned parts f of the cross-bar at F. The forward pivots of the beams or drag-bars are shown at e. The beams are to be supported, lifted, and lowered by means of the devices now to be described.

H is a radius-bar supported upon and extending upwardly from the transverse part of the crank-axle B. Preferably this bar H is pivoted to the ears i of the plate I, which is clamped to said axle B, as shown. The bar H is formed with a hook or projection H' at the upper end and an arm or extension h' at its lower end, each for a purpose to be described.

J is a suspension-bar pivotally connected to a beam or drag-bar E and extending up to the

upper end of the bar H. Preferably it is formed of a tube or pipe clamped at its lower end in the bifurcated support J', which is secured to the pivot-plate J², and the upper end is provided with a ferrule having a projection formed with a hook j and an aperture j². The hook or finger H' of the aforesaid bar H is inserted in the aperture j², whereby a flexible but sufficiently firm connection between the parts H and J is provided; and at the same time they are allowed to be quickly separated without requiring the removal of bolts or pins.

The bars H and J are provided with a regulator or holder, which is designated as a whole by K, to limit their backward movements and the downward movements of the beam when in its working position. As shown, this comprises a regulating connection or chain k, and in order to properly support the lower end of the chain it is secured to a bar k', the lower end of which is secured in the way to be described.

M is a bar pivoted at m to the above-mentioned short arm h' of the standard or upright lever-arm H. The bar M extends forward, as shown, and has its front end held in a guideway at m'. This guide can be provided by means of a clip o, secured to the frame-bars or secured to the brace-rod O, which extends upward from the wheel-spindle of the crank-axle B to the frame-bar D.

N is a lever pivoted at n to the front end of the sliding bar M. The upper part n' of lever N is provided with a hook n², and its lower part n³ is pivoted at n⁴ to the above-mentioned rod k', secured to the stop-chain k.

With the above-described parts of the regulating devices for limiting the backward movement of the bars H and J there is combined a lifting-spring mechanism for assisting the operator in lifting the beam into the non-operative position and which is designated as a whole by L and comprises a coiled spring l and an adjusting-bar l', pivoted at l' to the radius-bar H. The front end of the spring l engages with the hook n² of the lever N, and the rear end is adjustably connected with the bar l', which is provided with a plurality of teeth l', which constitute attachments or supports for this end of the spring.

At n⁵ there is a stop interposed between the

lever N and the sliding bar M, preferably by forming a shoulder or projection on the lever, which impinges upon the upper end of the bar. This stop n^5 operates, as one of its functions, to determine the normal working positions of the bars H and J and the beam E, and hence the normal depth to which the plows or cultivators will dig, and yet permits the said parts to be moved by the operator to cause either 10 a deeper or more shallow digging or cultivation, as desired. The force of the spring when the parts are in the position shown in full lines, Fig. 1, is sufficient to rock the lever N into position with the stop n^5 in engagement with the bar D, with the result that the force of the spring, which tends to pull forward the bars H and J and to lift the beam, is relieved, and they therefore tend to operate steadily in the position indicated. If it 15 is desired temporarily to have the cultivators run to a greater depth, the operator presses down with his foot on the usual stirrup with which the beam is provided, and in so doing forces the beam down and the upper parts of the bars J and H backward, rocks the lever N, so that its upper arm swings forward, carrying the stop n^5 out of engagement with the bar D and increasing the tension of the spring. As soon as the operator relieves the pressure 20 on the stirrup the parts are by the spring restored to the position shown in full lines in Fig. 1. It will be observed that there is provided a positive stop which serves to limit the extent to which the beam may be forced downward. This consists of the clip o, which is so disposed that the lever N at or near its pivotal connection with the bar M engages therewith after the bar has moved backward a short distance and positively prevents further 25 movement in that direction, for it will be seen that when the beam is forced downward it rocks backward the radius-bar H, and this in turn carries backward the bar M and the lever N until, as has been described, the stop o prevents further movement of these parts in the directions first indicated. The temporary lifting of the beam from its normal working position in order to cause more shallow digging or to pass obstructions may be performed by the operator in the usual way and 30 need not be described in detail.

Another function of the stop n^5 from that described is to render the connection between the spring and the outer or forward end of the bar M sufficiently rigid during the time the spring is operating as part of the lifting mechanism to assist in raising the beam into the inoperative or riding position. (Indicated by dotted lines in Fig. 1.) It will be observed 35 that during such operation of the spring the stop n^5 is forced and held into engagement with the bar M, so that the force of the forward end of the spring is transmitted directly backward to the bar M and through it to the radius-bar.

When the beams are in their normal working position, the following facts will also be

observed: The radius-bar H is inclined upward and backward somewhat, and the pivot m of the sliding bar M is up slightly above 70 the line which joins the pivots n and i, and hence the sliding bar M cannot act under the influence of the spring l to bring forward the parts H and J, as it is exerting a pressure which is nearly zero, and what little there is 75 is exerted backward upon the bar H, this being just enough to provide a species of lock, which, however, is yielding and is broken whenever the bars H and J are thrown forward to lift the beam. If the plow-beam E be 80 elevated, as by the operator lifting upon the handle at j' until the parts H and J have assumed the position shown in dotted lines, Fig. 1, it will be seen that the pivot m has been rocked downward by the short arm h' 85 far enough to pass the line between the pivots i and n and that thereupon the spring l will act in a twofold manner: first, to draw directly forward on the radius-bar H at the point l' above the pivot i, and, secondly, to 90 push backward at the point m through the lever N and the bar M, said point m being now below the pivot i, the stop at n^5 at this time making the parts N and M practically 95 rigid, and the two supports or attachments for the spring, one for each end thereof, being movable and so connected with the beam-suspending devices that the spring becomes double-acting. In brief, it is merely necessary for the operator to impart a slight initial 100 lift to the handle j', after which the spring and the parts interposed between it and the beam automatically accomplish the rest of the lifting movement of the beam and carry it and themselves to the position indicated 105 by dotted lines in Fig. 1. During the latter part of this movement the regulating device K becomes inactive, it assuming substantially the position shown in dotted lines in Fig. 1. When, inversely, the beams are to 110 be returned to their working position, it is merely necessary for the operator to reach forward from his seat and pull backward with a force not great upon the handle j', whereupon the radius-bar H rocks back toward the 115 position in full lines in Fig. 1, and as soon as it brings the pivot m above the line of the pivot i the beam will be held in working position.

It will be understood that as many beams 120 and sets of lifting and holding devices may be employed as are desired.

I do not limit myself to all of the detail parts which I have shown for the purpose of illustrating an entire machine, as there can be 125 variations in several respects without departing from all of the features of my improvements. To those acquainted with such implements numerous ways will suggest themselves of applying the very desirable advantages incident to a double-acting spring of the character herein presented which will not necessitate the use of the details shown and which I for some reasons prefer, for it will 130

be seen that this part of the machine consists principally in having in combination with the vertically - adjustable cultivator - beam a spring, a movable carrier for each end of the 5 spring, and means for connecting these spring-carriers with the rear part of the beam, said parts being so arranged that both ends of the spring shall exert a force through the connecting devices upon such rear part of the beam. This combination broadly I do not herewith claim; but I have claimed it in my other application pending herewith, No. 594,580, filed June 6, 1896. In my said earlier application I provide for accomplishing 10 some of the functions attainable by my present invention by having two springs, one to serve principally as a lifting-spring to assist in counterbalancing the gang-beam while it is being raised above the ground, and the 15 other at the proper time coming into effective play as a regulator for the shovels while at work in the soil. In the present case both of these more or less independent and distinguishable functions can be and are performed by one spring. The relative arrangement of the parts is such that the power of the regulator becomes greater and greater as the power of the lifter lessens, and vice versa, by which expedient the operator without 20 un- 25 due effort can quickly shift the shovels in the soil by easy command of the regulator devices, while the lifter devices come more and more to his aid as a counterpoise for the weight of the beam on raising the shovels 30 from the working position.

I am aware of the fact that prior to the date of this patent it has been proposed to substitute a compression-spring arranged to 35 tend to expand forward and backward and bearing against an arm extending forward and downward from a rock-lever or radius-arm and similar to the arm herein indicated by h' and bearing at the other end against a hinge-lever similar in certain respects to that 40 herein at N, said lever being connected with the rock-lever or radius-arm by means of a chain or equivalent, such as shown herein at K, devices of the character referred to being illustrated in the patent, No. 579,182, to M. Sattley, and while I do not herein claim specifically a compression-spring—that is, one which 45 works expansively forward and back—as a particular form I wish it understood that such mechanisms come within the scope of 50 my invention in so far as they provide for exerting spring-power in substantially the way I have described, and in this connection I call attention to the fact that there can be inversion in well-known ways in a number of 55 respects as concerns the parts shown. In some earlier machines the spring action is arranged to be exerted more directly upon the suspension - bar, link, hand-lever, or mast J instead of through the medium of the radius-bar II. Hence, so far as the novel features 60 of my invention are concerned, I do not exclude such matters of inversion or change, as

many modifications can be made by those acquainted with the art without departing from these features properly considered.

The regulating device at K is adjustable to regulate or vary the positions of the shovel-points when at work—as, for instance, by having a series of perforations or hooks at one end of said device, such as those in the lower end of the lever N, with one or another of which the end of the bar h' may be engaged, or by engaging one or another of the links of the chain h with the hook j at the upper end of the radius-bar. As will be seen, either one of these 70 adjustments operates to change the position of the part K and to change the tension of the spring l . As the beam approaches its uppermost or riding position the pivot at j^2 at the free end of the radius-bar becomes directly aligned with the pivot i for the heel of said radius-bar and with the pivot at J^2 at the bottom of the suspension-rod. As the pivot j^2 reaches and passes this "dead-line" 75 the weight of the beam and other parts acts 80 to hold and draw down the free end of the radius-bar and keep the parts in their position of rest with the suspension-rod bearing against the axle. The forwardly-curved ferrule or terminal at the upper end of the suspension-rod enables the pivot at j^2 to reach 85 or slightly pass the dead-line described. The advance of the radius-bar toward the dead-line constantly lessens the tension of the 90 spring-lifter. This loss is corrected by reason of the direction of the pull and the point 95 of attachment for the lifter at the radius-arm. Being applied near the heel of the radius-bar, the short leverage of the lifter is 100 exerted at best advantage during the traverse of the radius-bar past the vertical. Hence 105 the counterbalancing effect of the lifter remains practically uniform throughout the shift. On the contrary, if the shovels are 110 forced into the soil from their normal working lines it is the spring-regulator, comprising the chain at h , which comes more and more into play. As the beam is lowered the 115 regulator with its long leverage upon the radius-bar exerts an increasing power, whereas the lifter, although distended, exerts its force with lessening effect.

I am further aware that it has been proposed to employ a horizontally-arranged contraction lifting-spring so disposed that it can 120 be used either for lifting or for cushioning or regulating the short oscillations vertically of the shovels when at work, said spring having combined with it a mast or suspension-rod extending up from the beams, a rod extending 125 downward and forward from the suspension-rod, a short radius-bar or lug-like lever extending forward from the cross axle-bar, and an arm or short bar pivoted to the lug-like radius-bar and connected to the spring, 130 such devices being shown in the patent to E. Waterman, No. 579,936, and I regard this as another way of embodying some of the features of my invention—namely, those inci-

dent to having a horizontal lifting-spring combined with parts which permit it when the beam is in working position to act as a resilient stop, regulator, or cushion and permit it after it starts up from the working position to exert an increased efficiency or power in lifting the beam to its place of rest.

What I claim is—

1. In a cultivator of the hammock type, the combination of the main frame, the beam hinged thereto, a radius-bar or lever pivoted to and extending up from the frame, a suspension-bar connecting the radius-bar and beam, and a lifting-spring having two different connections with the radius-bar, through one of which connections it acts as a lifting-spring and through the other of which connections it acts as a regulator when the beam is in working position.
2. In a cultivator of the hammock type, the combination of the main frame, the beam hinged thereto, a radius-bar or lever pivoted to and extending up from the frame, a suspension-bar connecting the radius-bar and beam, a lifting-spring connected with the radius-bar, and means whereby said spring is also operatively joined with the beam through another connection than its first-mentioned connection with the radius-bar, to act as a regulator.
3. In a cultivator of the hammock type, the combination of the main frame, the beam hinged thereto, a radius-bar or lever pivoted to and extending up from the frame, a suspension-bar connecting the radius-bar and beam, a lifting-spring connected with the radius-bar, and means whereby said spring is connected operatively with the radius-bar at a point above its first-mentioned connection to act as a regulator.
4. In a cultivator, the combination of the main frame, a beam hinged thereto, a radius-bar pivoted to and extending up from the frame, a suspension-bar, regulating devices comprising a spring for controlling the position of the beam while working, and means whereby said spring is also operatively connected with the radius-bar to serve as a lifting-spring.
5. In a cultivator, the combination of the main frame, a beam vertically adjustable relative to the frame, the upwardly-extending radius-bar pivotally connected with the frame, means for suspending the plow-beam from the radius-bar at a point above the main frame, a regulating connection united with the radius-bar, comprising a spring and an intermediate movable member which limits the backward movement of the radius-bar, and another connection between said movable member and the beam whereby the spring also serves as a lifting-spring.
6. In a cultivator, the combination of the main frame, a plow-beam vertically adjustable relative thereto, a pivoted radius-bar rising from the main frame, means for suspending the beam from the radius-bar, and

a regulator comprising a spring and pivoted lever connected with the radius-bar for controlling the backward movement of the same, 75 said spring being also arranged to exert lifting force upon the beam.

7. The combination of the main frame, the beam vertically adjustable relatively thereto, the pivoted radius-bar extending upward 75 from the frame, means for suspending the beam from the radius-bar, a regulating-spring connected with the radius-bar to limit its backward movement, said connection comprising a pivoted lever, a stop which limits 80 the regulating action of the spring, and means whereby said spring is connected with the beam to exert a lifting force upon the same.

8. The combination of the main frame, the beam vertically adjustable relative thereto, a 85 pivoted radius-bar extending upward from the beam, means for suspending the beam from the radius-bar, a connection with the radius-bar for limiting its backward movement, a lifting-spring for the beam, means 90 whereby said spring is united with said regulating connection to control the vertical movement of the beam when in working position and a positive stop for limiting the downward movement of the beam beyond a certain point. 95

9. The combination of the main frame, the plow-beam vertically adjustable relative thereto, a radius-bar pivoted to the main frame, means for suspending the beam from the radius-bar, a connection for the beam and the radius-bar for controlling their movement when in working position, a spring for elevating the beam, means connecting the spring and said regulating connection whereby the latter is permitted to yield, and means for locking the radius-bar against the forward action of the spring when the parts are in working position. 100

10. The combination of the main frame, a 110 beam vertically adjustable relative thereto, a pivoted radius-bar extending upward from the frame, means for suspending the beam from the radius-bar, a connection for the radius-bar and the beam when in working position, a lock which tends to hold the parts in working position but yieldable to permit them to be lifted by the operator, and a spring connected both with the said regulating connection and the said lock. 115

11. The combination of the main frame, the beam vertically adjustable relative thereto, the radius-bar, means for suspending the beam from the radius-bar, a lifting-spring connected with the radius-bar above its pivot, means connecting the spring with the radius-bar below its pivot whereby each end of the spring has an operative connection with the beam to lift the same, the connection for limiting the movement of the beam when in working position, and means joining the said regulating connection with the spring whereby the latter operates also as a regulating-spring. 125

12. The combination of the main frame, the

- beam vertically adjustable relative thereto, means for suspending the beam adjustably from a point above the main frame, and connected to the beam near the rear end thereof, 5 a spring exerting force in one direction through the said rear suspending devices to elevate the beam, means moving in the opposite direction and actuated by the spring to assist in elevating the beam, and a stop or holder for preventing the beam from moving downward beyond the desired limit, substantially as set forth.
13. The combination of the main frame, the beam vertically adjustable relative to the frame, means connected to the beam, near the rear end thereof, for suspending it from a point above the main frame, a spring exerting force from one of its ends, through the said rear suspending devices, to elevate the 15 beam, a sliding bar connected with the other end of the spring, and also with the beam-suspending devices, and arranged, substantially as described, to lock such devices against forward movement when the beam is in working position, and also serving, when the beam is being lifted to transmit to the suspending devices the force of the spring from that end with which it is connected, to assist in lifting the beam, substantially as set forth.
14. The combination, in a cultivator, of the main frame, the vertically-adjustable beam, the radius-bar H connected to the beam, the bar l', the arm h', the regulator K connected to the radius-bar, and the spring connected 20 with the regulator, and also with the said parts l' and h', substantially as set forth.
15. The combination, in a cultivator, of the main frame, the vertically-adjustable beam, the means for suspending the rear end of the 25 beam, the lifting-spring for exerting in one direction a lifting force upon the beam, means for transmitting from said spring power in the opposite direction also for lifting the beam, and the holder K connected with the 30 said power-transmitting means, substantially as set forth.
16. The combination of the main frame, the vertically-adjustable beam, a radius-bar, means for suspending the rear end of the beam from the radius-bar, a spring drawing 35 upon the radius-bar to lift the beam, a sliding bar M connected with the radius-bar, a holder K to limit the downward movements of the beam when in working position, and a lever N pivotally connected with the bar M, to which lever are connected both the spring and the regulator, substantially as set forth.
17. The combination of the main frame, the laterally-swinging, vertically-adjustable, cultivator-beam, beam-suspending devices, a 40 spring, a connection interposed between one end of the spring and the beam-suspending devices, through which the spring is adapted to exert a lifting action on the beam when it is rising, and a connection between the other end of the spring and the beam-suspending
- devices, adapted to regulate the beam when in working position, substantially as set forth.
18. The combination of the main frame, the laterally-swinging, vertically-adjustable, cultivator-beam, the beam-suspending device extending upward and swinging forward when the beam rises, and a combined lifting and regulating spring, having devices situated operatively between one end thereof and the beam through which the spring tends to hold the beam in working position, and devices interposed between the other end thereof and the beam-suspending devices through which the spring acts to lift the beam to its elevated position, substantially as set forth.
19. The combination of the main frame, the laterally-swinging, vertically-adjustable, cultivator-beam, a combined lifting and regulating spring, devices interposed between one 70 end of said spring and the beam-suspending device, through which the spring acts to lift the beam from its working position, and a chain interposed between the other end of the spring and the beam-suspending devices 75 through which said spring acts to hold the beam in its working position, substantially as set forth.
20. The combination of the main frame, the laterally-swinging, vertically-adjustable, cultivator-beam, the radius-bar on the frame, the suspending rod or bar for the beam, the spring connected to said radius-bar, a supplemental vibratable lever connected to the spring, and means connected to said supplemental lever for holding it in position against the tension of the spring, substantially as set forth.
21. The combination of the main frame, the laterally-swinging, vertically-adjustable, cultivator-beam, the radius-bar on the frame, the spring connected to the radius-bar, a lever in front of the radius-bar and connected to the spring, said lever being adapted to vibrate and to move the forward end of the 95 spring forward, substantially as set forth.
22. In a cultivator of the class described, the combination of the radius-bar, the beam-suspending rod, the spring connected to the radius-bar, the vibratable lever in front of the radius-bar having one end connected to the spring and adjustable devices connected to the other end of said lever for varying the action of the spring, substantially as set forth.
23. In a cultivator of the class described, the combination of the radius-bar, the beam-suspending rod, the spring, a chain connected to the radius-bar at a relatively high point extending downward, and connected with and receiving power from the spring, a swinging 110 lever connected to the end of the spring, and a toothed bar for varying the position of the spring, substantially as set forth.
24. In a cultivator of the class described, the combination of the beam, the beam-suspending devices, consisting of the radius-bar 115 and the beam-suspending rod, the beam-lift-

ing spring connected at one end to the said beam-suspending devices, the hinged lever for the opposite end of the spring, and the holder K connecting the lever with the beam-suspending devices, substantially as set forth.

25. In a cultivator of the class described, the combination with the beam thereof, of the radius-bar, means for connecting said beam and bar, the spring connected to the radius-bar at a point relatively remote from its fulcrum, and means connecting the spring to the radius-bar at another point relatively near the fulcrum, whereby said spring is adapted to both control the beam when in working position and to elevate it therefrom to its up-
permost position, substantially as set forth.

26. In a cultivator of the class described, the combination with the beam thereof, of the radius-bar, the spring connected with the radius-bar near its fulcrum for lifting the beam, the connection interposed between the radius-bar and the said spring, and means for varying the connection between the regulating devices and the spring, whereby the pull of the spring upon such devices is adjusted, substantially as set forth.

27. In a cultivator of the class described, the combination with the beam thereof, of a radius-bar having two arms projecting in different directions from its axis, a spring, means for connecting said spring with one of the arms of said radius-bar, and means connecting the said spring with the other arm of said bar, one of said connecting means transmitting power from the spring for sustaining the beam in working position, and the other transmitting power from the spring for lifting the beam away from working position, substantially as set forth.

40. 28. In a cultivator of the class described, the combination with the beam thereof, of a radius-bar having two arms projecting in different directions from its axis, a spring, means for connecting said spring with one of the arms of said radius-bar, means for connecting the said spring with the second arm of the radius-bar, and another and separate connection between the spring and the second arm of the radius-bar, substantially as set forth.

29. In a cultivator, the combination of the main frame, the beam pivoted thereto near its forward end, the beam-suspending devices connected with the rear portion of the beam and consisting of a radius-bar pivoted to the frame and extending upward, and a suspension-rod between the radius-bar and the beam, a spring which serves to regulate the depth to which the shovels carried by the beam shall dig, a stop device arranged to determine the normal depth of digging, but which may be forced to permit deeper digging, and a positive stop for limiting the depression of the beam, substantially as set forth.

30. The combination of the frame, the vertically-adjustable beam, a radius-bar, means for suspending the beam from the said bar, a lifting-spring and locking means interposed between the radius-bar and the end of the spring remote from said bar, and arranged to lock or hold the radius-bar against forward movement when the parts are in working position, such lock being yieldable or breakable by the action of the operator in moving the parts to riding position, substantially as set forth.

31. The combination of the frame, the vertically-adjustable beam, means for suspending the beam from the frame, a lifting-spring, a movable connection between one end of the spring and the beam-suspending devices said connection consisting of two parts or members hinged or pivoted together, a stop whereby said parts are rendered rigid relative to each other, whereby the spring may transmit its force through them to the beam, and connections between one of the said pivoted or hinged parts and the beam-suspending devices and arranged to move said parts relative to each other upon their hinge or pivot against the action of the spring, substantially as set forth.

In testimony whereof I affix my signature in presence of two witnesses.

JOHN B. BARTHOLOMEW.
